UNITED STATES PATENT OFFICE.

JAMES D. REIFSNYDER, OF PHILADELPHIA, PENNSYLVANIA, ASSIGNOR TO STOKES & SMITH COMPANY, OF SUMMERDALE, PHILADELPHIA, PENNSYLVANIA, A CORPORATION OF PENNSYLVANIA.

WRAPPED PACKAGE.

1,257,393.

Specification of Letters Patent. Patented Feb. 26, 1918.

Application filed December 16, 1915. Serial No. 67,175.

To all whom it may concern:

Be it known that I, JAMES D. REIFSNYDER, a citizen of the United States, residing in Olney, Philadelphia, county of Philadelphia, State of Pennsylvania, have invented new and useful Improvements in Wrapped Packages, of which the following is a specification.

This invention relates to the wrapping of small articles of regular form, that is, having opposite parallel faces, and an object of the invention is to produce a wrapped article of this form embodying a wrapper of very simple form which is applied to the article so as to leave a portion of one face of the article exposed to view, but with the wrapper applied in such a way that it retains itself upon the article. While the invention may be applied in the wrapping of an article of any kind, having opposite parallel faces, it is very useful when employed in the wrapping of books or catalogues to prepare them for being sent through the mail, the general purpose being in this instance, to leave exposed a portion of the book or catalogue so that the character of the contents of the package will be evident to the eye.

A further object of the invention is to attain my objects by using a wrapper of very simple form applied in a very simple manner and in such a way that if desired, the wrapper can be applied readily by machinery.

Further objects of the invention will appear hereinafter.

The invention resides in the wrapped article forming the subject matter of the present invention.

The invention consists in the wrapped article or book having features of the invention set forth hereinafter.

In the drawing:—

Figure 1 is a perspective showing substantially the first step or act of applying the wrapper to a book.

Fig. 2 is a perspective showing substantially the second step or act in applying the wrapper.

Fig. 3 is a perspective showing substantially the next step or act in applying the wrapper.

Fig. 4 is an end elevation showing the upper or lower end of the book and illus-

trating the next step or act in applying the wrapper.

Fig. 5 is an elevation showing the front edge of the wrapped book.

Fig. 6 is a perspective illustrating another step or act in applying the wrapper. 60

Fig. 7 is an elevation showing one end of the wrapped book with the wrapping operation nearly completed.

Fig. 8 is a perspective of the completely wrapped book. 65

In practising my invention I prefer to employ a one piece wrapper such as the wrapper 1, which may be of substantially rectangular form and of slightly greater width than the book 2 to which the wrapper 70 is to be applied; near the middle portions of a longitudinal edge and one of the end edges I prefer to provide adhesive zones or areas 3 and 4; the article to be wrapped which is supposed to have opposite parallel 75 faces, for example, a book, is then laid upon the wrapper so that its length extends with the length of the wrapper and the upper edge 6 and lower edge 7 of the wrapper are then folded in succession down upon the 80 front side 5 of the book and overlapping each other in the manner indicated in Fig. 2 so that the adhesive zone 4 comes between the overlapping edges and secures these edges together lying flatly against the upper 85 side of the book, and so that the wrapper forms an envelop fitting snugly or neatly around the book. In this way the edges 6 and 7 unite to form an upper covering flap 8 for the upper side of the book and the body 90 portion of the wrapper forms a lower covering flap 9 for the lower side of the book. These flaps present integral front extensions 10 which project beyond and overhang the forward edge 11 of the book. A portion of 95 the wrapper or envelop forms an edge flap 12 covering the upper edge of the book, and another portion of the wrapper forms an edge flap 13 covering the lower edge of the book and these upper and lower edge flaps 100 12 and 13 have front extensions 14 at the front edge of the book and back extensions 15 at the back of the book. I proceed to fold in the extensions 14 against the front edge 11 of the book preferably substantially 105 as shown in Fig. 3, that is in such a way as to enable the edges 10 to be folded down successively, and so that the adhesive area

3 will secure these edges together and close the wrapper at the forward edge of the book. I also fold inwardly the edge extensions 15 so that they lie flat against the back 5 16 of the book (see Fig. 6) and this leaves the back edge of the partially wrapped book with two backwardly projecting extensions 17 which form integral extensions from the side flaps 8 and 9 of the wrapper. I then 10 place adhesive 18 on the outer faces of these projecting extensions, and I then fold these extensions 17 outwardly in the manner indicated in Fig. 7 and then press them down flatly against the outer side faces of the 15 wrapper so that they become secured in this position (see Fig. 8). By folding inwardly the extensions 15 in the manner indicated in Fig. 6, a back flap extension 20 is formed which lies flat across and against the back 20 edge or face of the book and when the flaps 17 are folded over, a gusset fold flap 19 is formed which lies flat upon the outer side of the side flaps and connects the side flap extension 17 with the back flap.

25 By applying a wrapper to a book or catalogue in the manner described, it is evident that the flap extensions 20 will leave a large portion of the back 16 of the book exposed to view so that it will be evident to the eye 30 that the package contains a book; the back flaps 20 lying as they do, near the ends of the book engage the adjacent ends of the back of the book and retain the book in the wrapper, that is they prevent the wrapper 35 from being slid off the book.

At the side flaps 17 evidently there are two thicknesses of material thereby effecting a substantial reinforcement of the material at the edges of the opening which is formed 40 between the flaps 20.

While I prefer to employ two back flap extensions 20 it is obvious that if only one such extension were employed it would still operate to retain the book within the 45 wrapper.

It is evident that all of the operations described above are very simple and could readily be performed by machinery and consequently the practice of my invention enables 50 large quantities of books or catalogues to be wrapped very economically for mailing purposes. If desired, the adhesive which is used may be applied in a moist state to the wrapper or if desired, it may be used as 55 a dry gum which is previously applied to the wrapper and which is moistened thereafter to enable it to adhere to the parts which it is intended to attach together.

While the invention is particularly useful 60 when applied to a book or catalogue, it is evident that it may be applied in the wrapping of any article which is to have an exposed or partially exposed face after being wrapped.

65 It is understood that the particular rela-

tion of the wrapper to the article and manner of folding the wrapper about the article suggested above, is suggested only by way of example and I do not limit myself to that particular relation of the wrapper and the 70 article. One of the essential features however, is that in applying the wrapper to the article a face of the article is left exposed and an integral portion of the wrapper is folded across and against the exposed face 75 to retain the wrapper on the article. When this invention is practised, it is unnecessary to use wrapper blanks with slits openings cut therein which would entail a waste of paper. 80

It is also understood that the embodiment of the invention set forth herein is only one of the many embodiments or forms the invention may take, and I do not wish to be limited in the practice of the invention nor 85 in my claims to the particular embodiment set forth.

What I claim is:—

1. A wrapped package comprising an article and a wrapper applied thereto and secured thereon, said wrapper being of greater dimensions than the article and folded about and completely enveloping all walls of the article except one, the article serving as a form during the folding operation, said 95 wrapper having a portion thereof folded across and partially covering the said uncovered wall of the article.

2. A wrapped package comprising an article and a wrapper-blank of substantially 100 uniform width folded about and completely enveloping all walls of the article except one, said wrapper blank having a portion thereof folded across and partially covering the said uncovered wall of the article and constituting a retaining strap to prevent withdrawal of the article from its wrapper. 105

3. A wrapped package comprising an article and a wrapper-blank of substantially uniform width folded about and completely 110 enveloping all walls of the article except one, said wrapper having portions thereof folded across and partially covering the said uncovered wall of the article at separated points and constituting retaining straps to 115 prevent withdrawal of the article from its wrapper.

4. A wrapped package comprising an article and a one-piece wrapper-blank completely enveloping all walls of the article except one, said wrapper having a portion thereof folded across the said uncovered wall of the article and constituting a retaining strap to prevent withdrawal of the article from its wrapper, and the blank being 120 further folded to provide a reinforcement thereof along the edges adjacent the uncovered wall of the package.

5. As a new article of manufacture, a book having a one piece wrapper with front and 130

rear side covering flaps for the front and rear sides of the book and edge covering flaps for the upper and lower edges of the book, said front and rear side-covering flaps 5 having forward extensions folded inwardly and attached together at the front edge of the book, said upper and lower edge-covering flaps having extensions forming back flaps folded against the back of the book, 10 said side covering flaps having integral extensions at the back of the book connected by gusset folds with said back flaps and folded against the outer sides of the said side-covering flaps and attached thereto, there- 15 by leaving a portion of the back of the book exposed to view.

6. A wrapped package consisting of an article having opposite parallel faces and a substantially rectangular wrapper-blank folded 20 about and enveloping the article leaving one face thereof exposed, said wrapper having portions thereof folded across and engaging the exposed face of the article to retain the wrapper on the article and other portions 25 folded and secured to the body of the wrapper along the opposite longitudinal edges of the said exposed face of the article to reinforce the wrapper at said edges.

7. As a means for inclosing an article with 30 one article wall permanently exposed, a container formed from a wrapper foldable about the article and within which the article is positioned, the article serving as a form to determine the interior dimensions of the 35 container, said container having a retaining strap extending over said exposed wall to retain the article against removal, said strap being integral with opposing container walls.

8. As a means for inclosing an article with one article wall permanently exposed, a 40 wrapper of substantially uniform width and forming a container overlying the remaining walls of the article with a retaining strap extending over the exposed wall and connecting opposing container walls. 45

9. As a means for inclosing an article with one article wall permanently exposed, a 50 wrapper foldable about the article to form a container overlying the remaining walls of the article and having strap-like article-retaining means overlying the exposed wall and integral with and connecting opposing container walls, the article serving as a 55 form to control the interior dimensions of the container during the wrapping operation.

10. As a means for inclosing an article with one article wall permanently exposed, a 60 wrapper folded about the article to form a container overlying the remaining walls 60 of the article with predetermined edge portions of the wrapper folded over the exposed wall and forming straps overlying said wall and connecting opposite container walls, the article serving as a form to control the interior dimensions of the container 65 during the wrapping operation, said straps constituting means for retaining the article within the container.

In testimony whereof I have hereunto set 70 my hand in the presence of two subscribing witnesses.

JAMES D. REIFSNYDER.
